[57] **CLAIM**

The ornamental design for a portable order terminal with card reader, as shown and described.

DESCRIPTION

FIG. 1 is a top, front, right side perspective view of a portable order terminal with card reader showing our new design;

FIG. 2 is a top, front, right side perspective view thereof with a card reader attached to the front;

FIG. 3 is a top plan view thereof on an enlarged scale;

FIG. 4 is a bottom plan view thereof on an enlarged scale;

FIG. 5 is a right side elevational view thereof on an enlarged scale;

FIG. 6 is a left side elevational view thereof on an enlarged scale;

FIG. 7 is a top, plan view thereof on an enlarged scale, with a card reader attached to the front;

FIG. 8 is a right side elevational view thereof on an enlarged scale, with a card reader to the front;

FIG. 9 is a front elevational view thereof on an enlarged scale;

FIG. 10 is a rear elevational view thereof on an enlarged scale.
